(57) **CLAIM**

The ornamental design for a balancing weight for a vehicle wheel, as shown and described.

DESCRIPTION

FIG. 1 is a perspective view of a balancing weight according to the present invention;

FIG. 2 is another perspective view of the balancing weight shown in FIG. 1;

FIG. 3 is a top plan view of the balancing weight shown in FIG. 1;

FIG. 4 is a lateral right side elevation view of the balancing weight shown in FIG. 1;

FIG. 5 is a back side elevation view of the balancing weight shown in FIG. 1; and,

FIG. 6 is a front side elevation view of the balancing weight shown in FIG. 1.

The broken lines in each of the figures represent environmental structure and form no part of the claimed design.
